UNITED STATES PATENT OFFICE.

EDMUND A. PARKER, OF MERIDEN, CONNECTICUT.

NUTMEG CONTAINER AND GRATER.

1,079,434.

Specification of Letters Patent. Patented Nov. 25, 1913.

Application filed February 19, 1913. Serial No. 749,458.

To all whom it may concern:

Be it known that I, EDMUND A. PARKER, a citizen of the United States, residing at Meriden, in the county of New Haven and 5 State of Connecticut, have invented certain new and useful Improvements in Nutmeg Containers and Graters; and I do declare the following to be a full, clear, and exact description of the invention, such as will 10 enable others skilled in the art to which it appertains to make and use the same.

This invention relates to improvements in nutmeg containers and graters.

One object of the invention is to provide 15 a container for nutmegs having in connection therewith a grater which forms the cover for the container and is adapted to be removably fastened thereon.

Another object is to provide a device of 20 this character which will be simple, durable and inexpensive in construction, efficient in operation, and well adapted to the purpose for which it is designed.

With these and other objects in view, the 25 invention consists of certain novel features of construction, and the combination and arrangement of parts as will be more fully described and claimed.

Figure 1 is a side view of my improved 30 nutmeg container and grater. Fig. 2 is a central vertical section thereof. Fig. 3 is a perspective view of the container with the combined cover and grater removed, and Fig. 4 is a cross-sectional view of the device.

In the embodiment of the invention I 35 provide a container 1 which may be constructed of any suitable material but which is preferably formed of glass, porcelain or 40 the like. The container is here shown and is preferably in the form of a hollow cylindrical body open at its upper end and having its lower end shaped to form a base 2 upon which the device is adapted to stand 45 when not in use as a grater. The upper end of the body of the container is externally threaded for a short distance as shown at 3. The body or container 1 may be of any desired size but is preferably of sufficient size 50 for holding several nutmegs which when placed therein are protected from dust and kept in a sanitary condition ready for use when needed.

Adapted to be engaged with the container 55 is a combined grater and cover 4 comprising a tubular cylindrical body portion the

inside diameter of which is substantially the same as the outside diameter of the body of the container with which said body of the grater is engaged when not in use. The 60 cylindrical body of the grater is punched through from the inside to form a plurality of perforations 4^a the edges of which are turned outwardly and form a grating surface on the outer side of the body of the 65 grater.

On the upper end of the body of the grater is a cap 5 the inner surface of which at the upper end of the body of the grater is threaded as at 6 whereby the cap may be 70 screwed on to the upper end of the body of the container thereby fastening the cap and the body of the grater in position on the container. When in this position the cap 5 forms a tight closure for the container and 75 protects the contents thereof. The cap 5 may be plain or constructed in any desired ornamental design as shown.

When it is desired to use the grater 3 the cap 5 is unscrewed from the upper end of 80 the container and together with the cylindrical body of the grater is removed from the container after which the cap serves as a handle by which the grater is held in position to receive the nutmegs which are 85 rubbed on the outer grating surface thereof in the usual manner. After a sufficient quantity of the grated nutmeg has been obtained the remaining ungrated portion of the nutmeg may be replaced in the container 90 and the grater and cap replaced thereon in the manner described.

From the foregoing description, taken in connection with the accompanying drawings, the construction and operation of the 95 invention will be readily understood without requiring a more extended explanation.

Various changes in the form, proportion and the minor details of construction may be resorted to without departing from the 100 principle or sacrificing any of the advantages of the claimed invention.

Having thus described my invention what I claim is:

1. A device of the character set forth comprising a receptacle having an open top, a combined grater and cap having a body portion substantially the same height as the receptacle and adapted to telescope the same and to be detachably engaged therewith, 105 said cap being adapted to close the top of the receptacle when applied to it and to 110

form a handle for the grater when removed from the receptacle.

2. A nutmeg container and grater comprising a hollow cylindrical body open at its upper end, a grater comprising a cylindrical body closed at its upper end to form a cap, and having its sides perforated and the edges of the perforations turned outwardly to form an abrasive surface upon which the nutmegs may be grated and

means to removably fasten the grater and cap in position on said container to close the open end thereof.

In testimony whereof I have hereunto set my hand in presence of two subscribing witnesses.

EDMUND A. PARKER.
